UNITED STATES PATENT OFFICE.

LOUIS SCHNEIDER, OF MITTWEIDA, GERMANY.

DESIGN FOR A COMB-TEETH-CONTAINING SHEATH.

SPECIFICATION forming part of Design No. 31,297, dated August 1, 1899.

Application filed June 17, 1899. Serial No. 720,985. Term of patent 14 years.

To all whom it may concern:

Be it known that I, LOUIS SCHNEIDER, a subject of the King of Saxony, residing in the town of Mittweida, Kingdom of Saxony, German Empire, have invented and produced a new and original Design for a Comb-Teeth-Containing Sheath, of which the following is a specification, reference being had to the accompanying drawings, which form a part 10 of said specification.

Figure 1 illustrates a side elevation of a comb-teeth-containing sheath embodying my design; Fig. 2, a cross-section of the same, the view being taken along the line *a b* of 15 Fig. 1.

The leading features of the comb-teeth-containing sheath consists of a sheath substantially V-shaped in cross-section and open at both ends and along the entire length of one 20 side, whereby the sheath may be slid or moved over the teeth either lengthwise from either end, parallel to its own length and to

the back of the comb, or in a direction parallel to the length of the teeth.

In the drawings, A represents the sheath, 25 which is provided with comb-teeth covering sides *a*, that form a sheath which is substantially V-shaped in cross-section, as represented in Fig. 2 of the drawings, and which open at the ends for the reception of the teeth 30 of a comb.

I claim as my invention and desire to be protected therein by a patent thereon—

The design for a comb-teeth-containing sheath substantially as herein shown and described. 35

In testimony that I claim the foregoing as my invention I have signed my name, in presence of two witnesses, this 31st day of May, 1899.

LOUIS SCHNEIDER.
